UNITED STATES PATENT OFFICE.

MICHEL GUIET, OF PARIS, FRANCE.

AXLE-BOX FOR CARRIAGES.

SPECIFICATION forming part of Letters Patent No. 389,963, dated September 25, 1888.

Application filed March 27, 1888. Serial No. 268,682. (No model.)

To all whom it may concern:

Be it known that I, MICHEL GUIET, of the firm of Million, Guiet & Cie., at Paris, (Seine,) in the Republic of France, have invented Im-
5 provements in Axle-Boxes for Carriages, of which the following is a specification.

This invention relates to an improved lubri-
cator, consisting of a metal grease-box so ar-
ranged as to secure an effectual and economi-
cal lubrication of long duration. This lubri-
cator can be employed with ordinary axle or
other grease and presents the following ad-
vantages.

First. The suppression of overheating of
15 the axles, and consequently of binding action.

Second. Reducing to its minimum the wear
and tear of the axle-journals, washers, nuts,
and boxes.

Third. In patent axles for oil or grease the
20 oil-reservoir is dispensed with, and conse-
quently the false bearing which causes the
fracture of the axles. The box bearing on the
axle close to the collar or washer, the section
25 of the latter is increased by the difference of
diameter existing between the boss and the
barrel. The axle is thus strengthened.

Fourth. For carriages this lubricator has
this other advantage, that the grease-chambers,
of an ear shape, fit into the nave without pro-
30 jeeting above it and without weakening it.

The neat appearance of the wheel is not found
to be destroyed.

Fifth. Avoiding the leakage which is pro-
duced in ordinary oil or grease boxes, and
35 thereby preventing waste.

Sixth. Owing to defects in casting, there is
often a leakage of oil in the interior of the nave,
which spoils the wheel by percolating to the
spokes. This inconvenience is obviated by
40 the use of the improved box herein described.

Seventh. The lubricating can be performed
without taking off the wheels—a point of great
importance in the case of heavy vehicles with
large and ponderous wheels.

45 Eighth. This box is applicable to all kinds
of axles where oil or grease is employed, it
only being necessary to modify the proportions
according to the different needs.

Ninth. No special workmanship or tools are
required for fitting the box into the wheels, 50
it being within the capacity of every wheel-
wright.

Tenth. These boxes do not entail any modi-
fication of the axles; and in particular, when
combined with patent axles lubricated with 55
oil, they constitute a most perfect system of
lubrication.

In order that the said invention may be
fully understood, I shall now proceed more
particularly to describe the same, and for that 60
purpose shall refer to the several figures on
the annexed sheets of drawings, the same let-
ters of reference indicating corresponding
parts in both figures.

Figure 1 is a longitudinal section along the 65
axis of the axle or journal, and Fig. 2 is a front
view of the journal-box.

The box, as shown in Figs. 1 and 2, has two
ears, A, inside of which is a reservoir, B, for
holding the oil. At the end of the reservoir for
70 closing it is a stopper, C, having on its inner
side a spring, p, exerting a pressure on a pis-
ton or washer, P, which operates on the sur-
face of the lubricant, and causes it to flow out
through the channel D, to which feed the oil-
75 grooves E, which can be either straight or
helicoidal in shape.

I claim as my invention—

1. An axle-box having one or more lubri-
cating-chambers, and channels D, each com-
bined with a free piston in the said chamber,
a spring to act on the piston, and a stopper to
close the chamber and confine the spring, sub-
stantially as described.

2. An axle-box having one or more cham-
bers, B, channels D, and grooves E, in com-
bination with a free piston in the chamber, a
spring to act upon the piston, and a stopper
to close the chamber and confine the spring.

In testimony whereof I have signed my 90
name to this specification in the presence of
two subscribing witnesses.

MICHEL GUIET.
